US00D521992S

(12) **United States Design Patent** (10) **Patent No.:** **US D521,992 S**
(45) **Date of Patent:** **** May 30, 2006**

(54) **PERSONAL COMPUTER**

(75) Inventors: **Hisao Morooka**, Inagi (JP); **Mitsuhiko Kawami**, Tokyo (JP)

(73) Assignee: **Fujitsu Limited**, Kawasaki (JP)

(**) Term: **14 Years**

(21) Appl. No.: **29/225,586**

(22) Filed: **Mar. 18, 2005**

(30) **Foreign Application Priority Data**

Sep. 21, 2004 (JP) 2004-028577

(51) **LOC (8) Cl.** **14-02**

(52) **U.S. Cl.** **D14/316**

(58) **Field of Classification Search** D14/315-322;
D18/1, 2, 7, 11; 235/145 A, 145 R; 341/22,
341/23; 345/104, 156, 168, 169, 173, 87,
345/901-905; 361/680-686

See application file for complete search history.
